United States Patent Office

Des. 219,580
Patented Dec. 29, 1970

219,580

PORTABLE CABANA

Frank Fritz, Asbury Park, N.J., assignor to John Boyle
& Company, Incorporated, a corporation of New York

Filed Feb. 13, 1970, Ser. No. 21,426

Term of patent 14 years

Int. Cl. D25—04
U.S. Cl. D13—1

FIG. 1.

FIG. 2.

FIG. 3.

FIG. 4.

FIG. 1 is a side perspective view of my portable cabana, showing my new design;

FIG. 2 is a rear elevational view;

FIG. 3 is a view in side elevation opposite that side shown in FIG. 1; and

FIG. 4 is a top plan view.

I claim:

The ornamental design for a portable cabana, as shown.
